TYPE-WRITING MACHINE.

No. 890,120.

Specification of Letters Patent.

Patented June 9, 1908.

Application filed July 7, 1905. Serial No. 268,671.

To all whom it may concern:

Be it known that I, CHARLES J. BOND, citizen of the United States, and resident of Syracuse, in the county of Onondaga and State of New York, have invented certain new and useful Improvements in Type-Writing Machines, of which the following is a specification.

My invention relates to typewriting machines and more particularly to fractional line spacing devices and the object of said invention is to provide fractional line spacing devices which are simple in construction and efficient in operation.

To the above and other ends which will hereinafter appear, my invention consists in the features of construction, arrangements of parts and combinations of devices to be hereinafter described and claimed.

In the accompanying drawings, Figure 1 is a detail central longitudinal sectional view taken through the platen and showing the features of my invention applied thereto. Fig. 2 is a like view of the same, the view being taken at right angles to that shown in Fig. 1. Fig. 3 is a detail perspective view of a portion of the device to be hereinafter more fully described, and Fig. 4 is a sectional view taken on a line $x-x$ in Fig. 1 and looking in the direction of the arrow in said figure; the view showing the line spacing wheel and platen head in end elevation.

The platen comprises the usual external sheath 1 and internal wooden core 2. At one end of the platen is a platen head 3 which is secured to the platen by screws 4 that extend through holes in the platen head and take into the core 2 of the platen. This platen head has a shoulder 3^a seated within the core 2 and an inwardly extending sleeve 5 that constitutes a guide for a spindle 6 that extends through said sleeve and moves longitudinally therein. Extending outwardly from the platen head 3 is a sleeve 7 that is formed at its end as a peripheral bearing which is received in a bearing in the platen frame 8 so as to turn therein.

A collar 9 surrounds the sleeve 7 and bears at one end against the shoulder 10 on the sleeve and at the other end against the inner side of the platen frame. The sleeve 7 has a longitudinal slot 11 into which a pin 12 projects, the pin being carried by a spindle 13 received within the bore of the sleeve 7 and guided thereby in its longitudinal

movement. The outer end of the spindle 13 carries a finger wheel 14 secured thereto by a screw 14^a, whereas the inner end of said spindle bears against one end of the spindle 6, so as to move it longitudinally. The opposite end of the platen carries a part which is shown in detail in Fig. 3. This piece is in a sense a platen head and comprises a disk-like member 15 secured to a second disk-like member 16 by an intermediate cylindrical member 17, and an outwardly extending spindle or shaft-like member 18 projects from the disk-like member 16 and is seated in a bearing in the platen frame 8. A finger wheel 19 is removably secured by a screw 20 to the free end of the member 18 where it projects beyond the platen frame. The members 15, 16, 17 and 18 are preferably made in one piece and an end opening 21 is contained in the disk-like member 15 and the cylindrical member 17 for the reception of one end of the spindle 6. A set screw 22 is received in a threaded opening in the cylindrical member 17 and the inner end of said screw is received in a cut out portion 23 in the spindle 6, in order to limit the longitudinal movement of the spindle 6 and to prevent an accidental withdrawal of the spindle from its bearing 21. A coiled expansion spring 24 surrounds the spindle 6 and bears at one end against the inner face of the member 15 and at its opposite end against a wedging or actuating device 25 that is adjustably secured to the spindle 6 by a set screw 26. This wedge-like device is in the nature of a sleeve that has a beveled wedging face 27 thereon.

The tension of the spring 24 is exerted to move the spindle 6 in the direction of the arrow in Fig. 1 which tends to force the spindle 13 and the finger wheel connected thereto, to the right in said figure, whereas pressure exerted on the finger wheel to move it in a direction opposite to that indicated by the arrow in Fig. 1, will move the spindle 6 against the tension of the spring 24 and force the wedging device 25 to the left in said figure. The disk like portion 16 has holes at 28 for the reception of screws 29 which unite the platen head to the platen. The shoulder 30 on the platen head is received within the core of the platen and prevents any lateral displacement of the head on the platen. The disk like member 15 is recessed or apertured at 31 in opposite side edges 110

thereof and like apertures 32 are provided in the disk like member 16. Actuating levers 33 are seated in the bearing apertures 31 and 32 of the platen head so as to fill the apertures and cause the levers to rotate with the platen head and platen but to allow a lateral vibration of the levers in said bearing apertures. Each of the levers 33 extends longitudinally of the platen and has at its inner end a portion 34 that bears against the beveled portion 27 of the wedging device. A coiled contractile spring 35 is connected at its ends to the levers 33 and tends to draw the inner ends thereof towards each other and towards the wedging device 25. The outer end portion of each lever 33 is notched at 36 for coöperation with the disk-like member 16 of the platen head. The outer face of the disk-like member 16 constitutes a fulcrum against which the end 37 of each lever 33 is adapted to bear and on which the lever turns as a pivotal center when actuated by the wedging device 25. The outer edge portion 38 on the end of each lever bears against the inner face of a line spacing ratchet wheel 39, which is formed with a central opening and collar 40 by which the line spacing wheel is seated on a shouldered portion 41 on the platen head and on which the line spacing wheel is adapted to turn.

A plate or platen head 42 is secured in place, after the parts thus far described have been assembled, by headed screws 43 that extend through openings in said plate and are received at their threaded ends within openings in the portion 41 of the platen head or frame, thus securely uniting the plate 42 to the member comprising the parts 15, 16, 17 and 18. Interposed between the plate 42 and the outer face of the line spacing wheel is a fiber washer or plate 44 so that the two metallic faces will not come into direct contact and an efficient frictional engagement may be maintained between the plate 42 and the line spacing ratchet wheel when an axial movement of the latter to the left in Fig. 1 is effected by the levers 33. A plate 45 is secured to the member 16 by headed screws 46 and this plate is perforated to receive the ends of the levers therethrough as indicated in Figs. 1 and 2. The walls 47 of the plate opposite the openings therein prevent the levers from dropping away from a position where they properly coöperate with the fulcrum face of the member 16 and with the line spacing ratchet wheel. A spring detent roller 48 coöperates with the teeth of the line spacing ratchet wheel in the usual manner.

It will be understood from the foregoing description, that pressure exerted upon the finger wheel 14 to effect a longitudinal movement of the spindle 6 towards the left in Fig. 1, will move the wedging device 25 to the left, thus enabling the inner ends of the levers 33 to be drawn closer together by the

spring 35, thereby releasing the pressure exerted by the levers on the line spacing wheel and the release of pressure thus effected enables the platen to be rotated by either of its finger wheels independently of the line spacing wheel. As soon as the operator releases endwise pressure on the finger wheel 14, the spring 24 will cause the wedging device to be moved to the right, thereby moving the inner ends of the levers 33 away from each other, thus exerting a pressure by the portions 38 of the levers against the line spacing wheel which results in effecting a very slight axial movement of the wheel to the left, thereby producing a frictional engagement between the line spacing ratchet wheel and the plate 42, so as to lock the line spacing wheel to the platen.

From the foregoing description it will be seen that I have provided a simple and efficient fractional line spacing mechanism in which I am enabled to employ long levers 33 to secure an efficient frictional engagement between the line spacing ratchet wheel and the platen in order to effectively lock the two in frictional engagement and prevent any accidental relative displacement between the line spacing ratchet wheel and platen when the two are engaged and that I am enabled to readily disconnect the devices by merely giving the finger wheel 14 a pressure sufficient to overcome the tension of the spring 24. It will be understood that the axial movement of the spacing wheel is so slight that it is not appreciable in the operation of the device; that is to say, it does not affect the relation of the line spacing wheel to the coöperating line spacing mechanism and detent roller.

It is apparent that instead of two independent spindles 6 and 13, a single spindle may be employed and that other changes may be made without departing from my invention.

What I claim as new and desire to secure by Letters Patent, is:—

1. In a typewriting machine, the combination of a platen, a platen head fixed to one end of the platen, a line spacing wheel that is adapted to turn with the platen or to afford a turning of the platen relatively thereto, levers for pressing the line spacing wheel axially of the platen into contact with the platen head, and means operating on said levers to release their pressure.

2. In a typewriting machine, the combination of a platen, a platen head fixed to one end of the platen, a line spacing wheel that is adapted to turn with the platen or to afford a turning of the platen relatively thereto, and hand actuated means fixed against rotation independently of the platen but movable longitudinally thereof for effecting a movement of the line spacing wheel axially of the platen and into and out of

frictional locking engagement with the platen head.

3. In a typewriting machine, the combination of a platen, a platen head fixed to one end of the platen, a line spacing ratchet wheel that is adapted to turn with the platen or to afford a turning of the platen relatively thereto and independently of the line spacing means, and levers contained within the platen and extending longitudinally thereof and which coöperate with the line spacing ratchet wheel, to effect a movement thereof axially of the platen to force the line spacing wheel into and out of engagement with the platen head.

4. In a typewriting machine, the combination of a platen, a platen head fixed to one end of the platen, a line spacing wheel that is adapted to turn with the platen or to afford a turning of the platen relatively thereto, levers contained within the platen and extending longitudinally thereof and which coöperate with the line spacing wheel to effect a movement thereof axially of the platen, to force the line spacing wheel into and out of engagement with the platen head, and a hand controlled wedging device that coöperates with said levers to actuate them.

5. In a typewriting machine, the combination of a platen, a fixed platen head, a line spacing wheel that is adapted to turn with the platen or to afford a turning of the platen relatively thereto, levers contained within the platen and extending longitudinally thereof and which coöperate with the line spacing wheel to effect a movement thereof axially of the platen, to force the line spacing wheel into and out of engagement with the platen head, a wedging device that moves longitudinally of the platen and coöperates with said levers to actuate them, a finger wheel, and means for actuating said wedging device by a movement of the finger wheel axially of the platen.

6. In a typewriting machine, the combination of a platen, a fixed platen head, a line spacing wheel that is adapted to turn with the platen or to afford a turning of the platen relatively thereto, and a plurality of levers that extend longitudinally of the platen and are connected to rotate therewith and are fulcrumed against a part secured to the platen and bear against the line spacing wheel and effect an axial movement of the line spacing wheel to force it into engagement with the fixed platen head and thus connect the line spacing wheel and the platen to rotate together.

60. 7. In a typewriting machine, the combination of a platen, a fixed platen head, a line spacing wheel that is adapted to turn with the platen or to afford a turning of the platen relatively thereto, a plurality of levers that extend longitudinally of the platen and

are connected to rotate therewith and are fulcrumed against a part secured to the platen and bear against the line spacing wheel and effect an axial movement of the line spacing wheel to force it into engagement with the fixed platen head and thus connect the line spacing ratchet wheel and the platen to rotate together, and a hand controlled wedging device coöperating with said levers to actuate them.

8. In a typewriting machine, the combination of a platen, a fixed platen head, a line spacing wheel that is adapted to turn with the platen or to afford a turning of the platen relatively thereto, a plurality of levers that extend longitudinally of the platen and are connected to rotate therewith and are fulcrumed against a part secured to the platen and bear against the line spacing wheel and effect an axial movement of the line spacing wheel to force it into engagement with the fixed platen head and thus connect the line spacing ratchet wheel and the platen to rotate together, a finger wheel that is adapted to receive a movement axially of the platen, and a wedging device operatively connected to said finger wheel and coöperating with said levers to actuate them when the finger wheel receives an axial movement.

9. In a typewriting machine, the combination of a platen, a fixed platen head, a line spacing wheel that is adapted to turn with the platen or to afford a turning of the platen relatively thereto, a finger wheel at the end of the platen opposite the line spacing wheel, a longitudinally movable spindle that is fixed to rotate with the platen, longitudinally extending levers that coöperate with said line spacing wheel to effect an axial movement thereof and to force said wheel into engagement with the fixed platen head, and an actuating device connected to said spindle.

10. In a typewriting machine, the combination of a platen, a fixed platen head, a line spacing wheel that is adapted to turn with the platen or to afford a turning of the platen relatively thereto, a finger wheel at the end of the platen opposite the line spacing wheel, a longitudinally movable spring restored spindle that is fixed to rotate with the platen, longitudinally extending levers that coöperate with said line spacing wheel to effect an axial movement thereof and to force said wheel into frictional engagement with the fixed platen head, and a wedging device connected to said spindle and coöperating with the levers to actuate them by a longitudinal movement of the spindle.

11. In a typewriting machine, the combination of a platen, a plate fixed to the platen at one end thereof, a line spacing wheel, a fibrous sheet between the fixed plate and line spacing wheel, and means for effecting a movement of the line spacing wheel axially of the platen, to maintain a frictional con-

nexion between the line spacing wheel and the fixed plate.

12. In a typewriting machine, the combination of a platen, an abutment thereon, a line spacing ratchet wheel adjacent said abutment, spring pressed levers acting normally to press said line space ratchet wheel against said abutment and thus causing the ratchet wheel and platen to rotate together during regular line spacing movements, and means adapted to cause said levers to release their pressure upon said ratchet wheel so as to enable the platen to be turned independently of said ratchet wheel.
13. In a typewriting machine, the combination of a platen, an abutment thereon, a line spacing ratchet wheel adjacent said abutment, spring pressed levers acting normally

to press said line space ratchet wheel against said abutment and thus causing the ratchet wheel and platen to rotate together during regular line spacing movements, releasing means coöperative with said levers to release their pressure upon said ratchet wheel so as to enable the platen to be turned independently of said ratchet wheel, and a spindle or rod movable longitudinally within the platen and coöperative with said releasing means.

Signed at Syracuse, in the county of Onondaga and State of New York this 5th day of July A. D. 1905.
